UNITED STATES PATENT OFFICE.

ISAAC W. FLECK, OF CHATTANOOGA, TENNESSEE.

FOLDING CAR-STEP.

SPECIFICATION forming part of Letters Patent No. 307,935, dated November 11, 1884.

Application filed July 22, 1884. (No model.)

To all whom it may concern:

Be it known that I, ISAAC W. FLECK, a citizen of the United States, and a resident of Chattanooga, in the county of Hamilton and State 5 of Tennessee, have invented certain new and useful Improvements in Folding Car-Steps, of which the following is a specification.

My invention relates to improved folding car-steps adapted to be readily folded up and 10 closed to prevent access to the car, or to be opened to allow access to the platform of the car.

My invention also relates to a gate which is mounted upon the mechanism which turns the 15 steps up and down, so as to close when the platform is folded up and open when the platform-steps are let down, all of which will be fully set forth in the description of the accompanying drawings.

20 Figure 1 is a front elevation of my improvement shown attached to the platform of a car in position for use. Fig. 2 is a top plan view of the same. Fig. 3 is a side elevation of my improvement attached to a car. Fig. 4 is an 25 elevation showing the rod on which the gate and operating mechanism journal. Fig. 5 is a central sectional view of the steps folded up. Fig. 6 is an elevation of the transmitting mechanism for folding and unfolding the steps.

30 A represents the corner-posts of an ordinary car; B, the nose-piece or outer sill of the platform; a, the outer edge of the ordinary platform; b, the vertical partition of the first step of the platform.

35 My folding steps are attached to the car as follows:

C represents a bracket attached to the sill of the car, in which is journaled a revolving shaft, D.

40 d represents the sill of the car at the edge of the platform, in which rod D also journals for its rear support. A similar journal-suspending rod, G, is attached to the opposite side of the car.

45 F represents a bracket attached to the nose-piece B, through the eye of which bracket-rod G journals, the rear end of said rod journaling in the platform, as shown at d', Fig. 2. To these rods D and G are attached my folding 50 steps.

c represents sprocket-wheels journaled upon the shafts D and G.

f represents a beveled gear keyed upon rod G.

H represents a bracket attached to the nose-piece B, in which is journaled a shaft, I. 55

h represents a segmental pinion keyed upon rod I, and meshing with the gear f, so that as the shaft I is turned in its journal-supports, rotary motion is imparted to rod G, and by 60 means of sprocket-wheels c and chain J an opposite rotary motion is imparted to shaft or rod D.

i represents rods which connect the terminal ends of the chain J or secure swivels K, so 65 that the chain may be taken up or let out. The shafts D and G are intended to move one-half a revolution as the chain J moves a corresponding distance over the sprocket c, which allows the link-rods i and swivels k to be employed without their passing over the sprocket-wheels. The upper end of rod I journals 70 in the bracket K, which is secured to the nose-piece B opposite the hand-rail K', as shown in Fig. 4.

0 1 2 represent the folding steps, which are made of separate pieces of metal or wood, and suspended to folding side plates 3 4 5 by hinges 6 7 8. These hinges may be of any style of construction, but a rule-joint hinge is 80 preferred. The side pieces 3 4 5 are in turn hinged to stationary side pieces L, as shown in Fig. 3, which are rigidly secured to the rods D and G, so that side pieces L act, in fact, as crank-arms to fold or unfold the steps 85 when the shafts D and G are turned. One of these folding crank end pieces, L, is shown in elevation in Fig. 3 attached to rod G. The inner end piece, L, attached to rod D, is the counterpart of this in construction and operation.

The parts b 10 11 represent the vertical partitions of the steps, the part 11 being attached to step 2, part 10 to step 3, the part b being stationary or immovable. 95

In order that the steps 0 1 2 may fold up so as to be in a horizontal plane when folded up and form a platform, step 2 must move farther than step 1 and step 1 farther than step 0. Suppose the vertical portions of the step b to 100

be each eight inches in depth, then step 2 must be moved up twenty-four inches, step 1 sixteen inches, and step 0 eight inches, to be on a level.

In order that the parts may retain their relative positions, I provide lugs *l* on the steps 0 1 2, which move in slots *m* in the vertical partitions 10 11. These lugs and slots also form stays to prevent lateral movement of the parts when in position for use, and for this purpose the lugs *l* may have heads upon them to prevent their being pulled out of the slots *m*. It will be seen that the steps 0 1 2 are hinged to the folding side pieces 3 4 5, which are in turn hinged to the folding crank-arms on end pieces, *L*, also forming the side partitions of the steps.

The steps are folded as follows: When shaft *I* is turned, the segment *H*, meshing with gear *F*, revolves with it, and turns rod *G* to the right. The crank-arm or partition *L*, secured thereto, is moved half a revolution, so that it projects vertically upward instead of vertically downward, as shown in Fig. 3. This vertical position is obscured in Fig. 5 by the folding pieces 3 4 5, which are each separately hinged to the crank *L* by hinge-joints *O*, the steps 0 1 2 being hinged to parts 3 4 5 by joints 6 7 8. The opposite end of the steps, folding partitions *L*, and folding links 3 4 5 are attached to shaft *D*, and moved in the same manner simultaneously with the part just described.

E represents a weighted arm attached to rod *G*, so as to balance the weight of the steps and to assist in raising them. A spring coiled around the shafts might be used for the same purpose. The steps 0 1 2 are brought nearly on a level with the platform *a* when the steps are raised, and the hinged folding partition *L* and the parts 3 4 5 are doubled together and rise vertically above the plane *a a'*, as shown in Fig. 5. Thus the steps 0 1 2 serve as a platform-extension.

In order that the platform may be properly guarded, I mount a swinging gate, *N*, on the rod or shaft *I*, so that it may be turned by means of gate *N* a quarter of a revolution to move the shaft *D* and *G* one-half a revolution. Gate *N* is open when the steps are let down, and swings against the hand-rail at the end of the platform parallel with the nose-piece *B*. It is turned outward a quarter of a revolution to fold up the steps, and rests vertically across the front edge of this extension-platform, at the point *a'*. It is not shown in this position in the drawings.

p q represent brace-arms attached to the frame *r* of the gate.

P represents a latch which engages with a catch attached to the hand-rail of the platform 60 of the guard secured upon nose-piece *B*, and when the steps are folded up it is locked to a catch fixed upon the vertical end of the car, and holds the steps in a fixed position. It may be secured by a padlock or by other fastening devices, so as to prevent it being opened by unauthorized persons. This mode of constructing the steps allows them to be readily folded up when not desired to be used, and readily let down for use by simply opening 70 and closing the gate.

I do not wish to limit myself to the specific means for imparting motion to the folding-shafts *B* and *G*, or for conveying motion from one shaft to the other, as various mechanical 75 devices equivalent to those herein shown may be employed for that purpose, and still obtain the same general results as I have shown and described.

Having described my invention, what I 80 claim is—

1. In combination with the platform of a car, a series of folding steps, 0 1 2, suspended by link or hinge connections to cranks *L*, attached to the shafts *D* and *G*, substantially as 85 specified.
2. In combination with a series of folding steps suspended from crank-shafts *D G*, mechanism for imparting motion to the shafts *D G*, and operated by shaft *I*, substantially as specified. 90
3. In combination with shaft *I* and a series of folding steps journaled upon shafts which are operated by a vertical shaft, *I*, a gate, *N*, adapted to open and close simultaneously with 95 folding and unfolding steps, substantially as specified.
4. In combination with the platform of a car, the folding steps 0 1 2, suspended upon crank-shafts *D* and *G* by means of crank-arms 100 *L*, links 3 4 5, hinged thereto, and the hinged folding steps 0 1 2, operated by a driving-shaft, *I*, substantially as specified.

In testimony whereof I have hereunto set my hand.

ISAAC W. FLECK.
